UNITED STATES PATENT OFFICE

ALBERT JONES HUTCHINGS, OF ALLSTON, MASSACHUSETTS, ASSIGNOR TO C. A. CUNNINGHAM CO., OF BOSTON, MASSACHUSETTS, A CORPORATION OF MASSACHUSETTS

ANCHOR

Application filed February 26, 1929. Serial No. 342,926.

The present invention relates to anchors, and more particularly to devices adapted to be anchored to the walls of buildings for the purpose of safeguarding window cleaners against accidentally falling to the ground when cleaning windows from outside the building.

Window cleaners are accustomed to wear safety belts to which are secured a rope or ropes the ends of which are provided with terminals that are readily secured to, and released from, the above-mentioned anchors. Different kinds of anchors are employed in accordance with the nature of the building wall near the windows,—one kind, for example, for wooden walls, another for brick walls, and others for stone, marble, concrete or other masonry walls (which will hereinafter, for brevity, be referred to under the single word "stone"). Great difficulties have been experienced with anchors intended for use upon stone building walls. This is because the anchors must be embedded either in the cracks between the stones or within holes drilled in the stones. In the former case, the choice is practically limited to horizontal cracks, because vertical cracks are very few near a window; and in the latter case, no satisfactory way has yet been found for mounting an anchor securely enough in a drilled hole to ensure the window-cleaner's safety, and it is obvious that a weak anchor, upon which reliance is placed, is worse than none at all.

A very effective anchor bolt, particularly adapted for use with stone building walls, using the term "stone" as defined above, is disclosed in patent to Cunningham No. 1,574,471 of February 23, 1926. The object of the present invention is to improve upon the anchor bolt of the said patent. With this end in view, the invention consists of the improved anchor a preferred embodiment of which is hereinafter described, illustrated in the accompanying drawings and defined in the appended claims.

In the accompanying drawings, Fig. 1 is a perspective view, partly in section and broken away, of a stone wall, showing a preferred anchor in position; Fig. 2 is a horizontal sec-

tion of the same; Fig. 3 is a view corresponding to Fig. 2 of a modification; and Fig. 4 is an elevation of the modification shown in Fig. 3.

In Figs. 1 and 2, an anchor constructed in accordance with a preferred embodiment of the present invention is shown embedded in the mortar 21 between two stones 2 and 4 of a stone building wall. The anchor comprises a bolt arm 6 having two substantially parallel bolts 8 and 10 disposed in substantially vertical alignment and projecting from the bolt arm at right angles to the bolt arm. The bolts 8 and 10 have bolt heads joined to the bolt arm 6 by necks 30 and 32, respectively. The bolt arm 6 is of dimensions substantially greater than the thickness of the mortar 21, as illustrated, and lies flat against the stones of the wall, and the bolts 8 and 10 are positioned one on each side of the mortar, as shown. Two of these anchor bolts are, in practice, positioned one on each side of the window, and the terminals of the ropes from the window cleaner's belt are adapted to be fastened to the bolts 8 and 10 of each anchor. The lower bolts 10 are adapted to sustain the window cleaner while at work, and the upper bolts 8 are adapted to carry his weight in case he should slip or fall.

An anchor arm 12 projects from the bolt arm in a plane at right angles to the plane of the inner surface 22 of the bolt arm and about halfway between the bolts 8 and 10. In those types of stone building walls that are provided with wooden beadings 24, and particularly where the beading projections 24 are situated as close to the surface 15 of the wall as illustrated in Figs. 1 and 2, it is naturally desirable to locate the anchor bolts as far away from the surface 15 as possible, to reduce the chance of the anchor bolt loosening its hold upon the mortar and pulling out of its anchorage through the surface 15. The anchor arm 12 is, therefore, caused to extend out from the bolt arm 6, in the said plane, at an angle to the inner surface 22 of the bolt arm 6, so that the free extremity 14 of the anchor arm 12 may be embedded in the mortar at a point further away from the surface 15 than the other extremity of the anchor

arm. The anchor arm 12, in its preferred embodiment, is flat and tapers from the point where it joins the bolt arm to the said free extremity 14. If the anchor arm 12 were of the same width throughout, in the form of a wide, flat member, it would weaken the holding action, because decreasing the quantity of mortar that would be available to hold the anchor arm in place. The tapering construction, besides being more economical than would be an arm of equal width throughout, provides great strength where the anchor arm is wider, at the joint between the bolt arm 6 and the anchor arm 12, without weakening the holding power at the free extremity 14 of the anchor arm. The said free extremity is provided with an upstanding projection 16, parallel to the inner surface 22 of the bolt arm 6. A projection 20, at right angles to the projection 16, is disposed intermediately of the anchor arm. The anchor arm is adapted to be placed in position in the mortar 21 between the stones 2 and 4 before the stones have been laid in place, during the erection of the building. The projections 16 and 20, respectively, resist displacing forces in directions parallel and at right angles to the said inner surface 22. Two projections 16 and 20 are quite sufficient, since it is found, in practice, that the use of too many projections has a tendency to weaken, rather than strengthen, the anchoring effect, because, as there is so thin a layer of mortar between the stones, a multiplication of projections decreases the quantity of mortar employed and therefore weakens the joint as a whole. The stability is further increased by the inner surface 22 of the bolt arm 6 lying flat against the stones on each side of the mortar, as shown. The projections 16 and 20 may be caused to engage against sides of the bricks in the case of brick walls.

For the reasons before given, the bolt arm 6 is positioned as far as possible away from the surface 15, that is, with the side 25, that is, disposed in the direction of extension of the anchor arm 12, in contact with the beading 24. Under such circumstances, the bolts 8 and 10 of anchor bolts at present in use are so close to the beading 24 as to prevent free access to the bolts, and thus to interfere with the window-cleaner's slipping the terminals of his belt on and off the bolts 8 and 10. Such interference is particularly dangerous, as it might result in the window cleaner losing his footing and plunging to the ground. The bolts 8 and 10 are, therefore, positioned near the other side 27 of the bolt arm 6, as illustrated. This avoids the necessity of cutting the beading.

By reason of such decentering of the bolts 8 and 10, however, the bolt arm becomes weakened in two particulars. First, there is a tendency for the bolts 8 and 10 to become pulled towards each other and out of contact

with the building wall. Secondly, there is a tendency for the bolts 8 and 10 to become snapped off from the bolt arm 6, in the direction of the arrow of Fig. 2. To resist these tendencies, two strengthening ribs 26 and 28 project out from the bolt arm, the former longitudinally connecting the bolts 8 and 10, and the latter disposed transversely across the bolt arm. The rib 26 integrally connects the necks 30 and 32 of the bolts 8 and 10, respectively, and merges into the inner ends of the necks, as illustrated. It resists strains set up in the bolt arm by pulling forces exerted upon the bolt arm in a direction outward of the bolt arm. The rib 28 resists strains set up in the bolt arm by pulling forces exerted upon the bolts in a direction transverse to the bolt arm, as indicated by the arrow of Fig. 2. A very effective, yet economical construction is thus provided.

In cases where steel walls 34 are employed, the anchor arm 12 may be eliminated, and the bolt arm 6 widened out to provide screw eyes 36, as shown in Fig. 4.

It will be obvious to persons skilled in the art that changes may readily be effected without departing from the spirit of the invention, a preferred embodiment of which has been illustrated and described. All such changes and modifications are desired to be included within the scope of the appended claims.

What is claimed is:

1. An anchor comprising a bolt arm adapted to be secured to a building wall, two necks carried by the bolt arm and projecting out from the bolt arm and vertically disposed one above the other when the anchor is secured to the building wall, a bolt head carrier at the outer end of each neck, and a strengthening rib projecting out from the bolt arm and longitudinally connecting the necks and merging into the inner ends of the necks, the strengthening rib being adapted to resist strains set up in the bolt arm by pulling forces exerted upon the bolts in a direction of the bolt arm.

2. An anchor comprising a bolt arm adapted to be secured to a building wall with one side of the bolt arm in contact with a projection of the building wall, two bolts carried by the bolt arm at the other side of the bolt arm and vertically disposed one above the other when the anchor is secured to the building wall, whereby free access may be had to the bolts without interference by the projection, a strengthening rib longitudinally connecting the bolts and projecting out from the bolt arm for resisting strains set up in the bolt arm by pulling forces exerted upon the bolts in a direction outward of the bolt arm, and a strengthening rib disposed transversely across the bolt arm for resisting strains set up in the bolt arm by

pulling forces exerted upon the bolts in a direction transverse to the bolt arm.

3. An anchor comprising a bolt arm and an anchor arm extending at an angle from the bolt arm, the anchor arm being of dimensions such that it is adapted to be embedded substantially horizontally in the mortar of a building wall, the bolt arm being of dimensions substantially greater than the thickness of the mortar, whereby the bolt arm is adapted to engage against the building wall with the side of the bolt arm in the direction of extension of the anchor arm contacting with a projection of the building wall, two bolts carried by the bolt arm at the other side of the bolt arm, whereby free access may be had to the bolts without interference by the projection, one of the bolts being adapted to be positioned above the mortar and the other below the mortar, a strengthening rib longitudinally connecting the bolts and projecting out from the bolt arm for resisting strains set up in the bolt arm by pulling forces exerted upon the bolts in a direction outward of the bolt arm, and a strengthening rib disposed transversely across the bolt arm for resisting strains set up in the bolt arm by pulling forces exerted upon the bolts in a direction transverse to the bolt arm.

In testimony whereof, I have hereunto subscribed my name.

ALBERT JONES HUTCHINGS.
